UNITED STATES PATENT OFFICE

HARRY ACKROYD, OF EAST CHICAGO, INDIANA, AND ALFRED W. POWELL, OF CHICAGO, ILLINOIS

UNCOUPLING DEVICE FOR RAILWAY CARS

Application filed September 15, 1928. Serial No. 306,230.

The present invention relates to improvements in uncoupling devices for railway cars, one object of the invention being the improvement of the apparatus as shown in our U. S. 5 Patent No. 1,602,316, dated October 5, 1926, and relating more particularly to the construction of the operating rod and the mounting thereof relatively to the pin-actuating mechanism.

10 A further object of this invention is the provision of a novel mounting and construction of operating rod in which the inner terminal of the rod is so constructed as to form the journal for the oscillatory mounting of 15 said rod and at the same time form the fulcrum upon which one of the operating levers for the pin is mounted, there being provided a single detachable mounting whereby the rod is readily installed or removed.

20 With the foregoing and other objects in view, which will appear as the description proceeds, the invention resides in the combination and arrangements of parts and in the details of construction hereinafter described 25 and claimed, it being understood that changes in the precise embodiment of the invention herein disclosed can be made within the scope of the claim without departing from the spirit of the invention.

30 In the accompanying drawings:—

Figure 1 is an end view of a portion of a freight car and the coupling member with the present invention applied thereto;

Figure 2 is a cross-section through the end 35 of the car with the present device applied, broken lines showing the elevated position of the present device;

Figure 3 is a cross-section through the body of the car, looking downwardly upon the 40 present mechanism;

Figure 4 is a cross-section taken on line 4—4 of Figure 1;

Figure 5 is a top plan view of the inner rod journalling member;

45 Figure 6 is a front elevation thereof;

Figure 7 is a top plan view of the outer rod journalling member; and

Figure 8 is a front view thereof.

Referring to the drawings, the numeral 50 9 designates the inner journalling member

of the present construction, the base of same being provided with the apertured portions 10 for the reception of securing means, such as rivets 11, for attaching same to the angle plate 12 at the rear end of the car above the 55 coupler C. Formed integrally with the base of the member 9 are two upstanding parallel apertured lugs 16, the purpose of which will presently appear.

The base of the outer rod-supporting member 13 is provided with apertures 14 for the reception of securing means, such as rivets 15, which attach the same to the angle plate 12 of the car. This member is provided with the upstanding portion 17 which is provided with the two parallel right-angled arms 18 and 19 having aligned apertures 20 for the reception of the cotter pin 21 which removably holds the seal block 22 between said arms, as clearly illustrated in Figure 4, so 60 that the operating rod 23 may be securely held at this point for oscillatory movement.

As shown in Figures 1 and 3, the rod 23 is angularly bent at its outer end to form an operating handle 24 and adjacent its other end is obliquely bent, as at 25, and then bent into parallelism with its main portion to form an offset portion 26. It is then bent back toward its outer end to form a hooked terminal 27, the axial center of which is in 65 line with the axial center of the main portion of the rod. The hooked terminal 27 is adapted to be slid into the apertured lugs 16 of the inner supporting member 9. In this manner, the members 9 and 13 constitute 70 the support for the operating rod 23, and in assembling same it is merely necessary to insert the terminal 27 into the lugs 16 and move the body of the rod into the space between the arms 18 and 19 of the supporting member 13 and then attach or secure the block 22 in the position as shown in Figure 75 4, the single cotter 21 being employed to hold the rod in the properly assembled position.

The remaining part of the present device 80 is similar to that shown in the previously mentioned patent, the reduced apertured end of the outwardly projecting lever 29 being pivoted upon the terminal 27 of the rod 23 between the two lugs 16 and positioned so 85 100

as to be engaged by the offset portion 26 of said rod to assume the several positions as illustrated in full and dotted lines in Figure 2. The outer end 30 of the lever 29 is connected to the link 31 which, in turn, is connected to the coupling pin 32 in the usual manner.

The operation of the present device is similar to that shown in our previous patent, it merely being necessary to operate the handle 24 in such a manner as to rock the rod 23 and move the portion 26 of the rod from the lowermost position illustrated in Figure 2 to the highest position, as there shown in dotted lines, the lever 29 being thus engaged.

By this construction, the operating rod is more securely mounted, the number of parts is reduced, and the cost of installation is lessened. Further the portion 26 is less liable to become bent out of proper relation to the handle 24 than it would be if its end was not supported by the member 9.

We claim:

An uncoupling means for railway cars, comprising a freely movable forwardly projecting coupling-pin lifting lever, spaced apertured members between which said lever is mounted and an operating rod for said lever, said rod having a hooked terminal and an offset portion adjacent and parallel to said hooked terminal, said hooked terminal extending through the apertures of said members and forming a fulcrum member for the lever and the offset portion being disposed below said lever to elevate the lever when said rod is rocked.

In testimony whereof we have hereunto set our hands.

HARRY ACKROYD.
ALFRED W. POWELL.
